PAGE 2

FIG.2.

FIG.3.

FIG.4.

Fig. 1 is a perspective view of a tire embodying my new design, it being understood that the full line portions are repeated throughout the circumference of the tire shown by means of broken lines;

Fig. 2 is a fragmentary plan view of the full line portions of Fig. 1;

Fig. 3 is a fragmentary side elevational view thereof, the opposite side being substantially the same; and,

Fig. 4 is a vertical cross-sectional view thereof, taken on line 4—4 of Fig. 2.

The dominant features of my design reside in the full line portions of the drawings.

I claim:

The ornamental design for a tire, as shown and described.
